DRUM BRAKE

Geoffrey Robert Greenbergh Gates, London, England, assignor to Automotive Products Company Limited, London, England

Application January 5, 1940, Serial No. 312,583
In Great Britain January 28, 1939

4 Claims. (Cl. 188—78)

This invention relates to drum brakes of the kind comprising a plurality of rigid arcuate shoes which are supported upon a back plate or equivalent fixed part of the brake, and are arranged to be moved outwards into engagement with the drum by spreading means.

It is the object of the present invention to provide an improved form and construction of adjusting device which is so arranged that the shoe is maintained in efficient co-operation with the spreading means and an anchorage device during all stages of lining wear. The invention is intended more particularly for use with brakes in which the ends of the shoes are formed with concave part-cylindrical surfaces which are adapted to co-operate slidably with the anchorage means so as to constitute in effect a pivotal mounting for the shoe end.

In an internal shoe drum brake a shoe is provided having its ends in engagement with an applying means and an anchorage respectively, and the present invention is characterised by the fact that said ends are formed upon two mutually separate members which are held in overlapping relationship and are adjustable upon one another to change the effective length of the shoe and thereby compensate for lining wear.

Thus in an internal shoe drum brake including a rigid arcuate shoe having a circumferential flange portion fitted with the usual lining material, the invention is further characterised by the fact that the shoe is provided with a terminal member which forms one end of the shoe and is adjustable relatively to the main part of the shoe in a circumferential sense, said terminal member having its inner end adjustably connected with the main part of the shoe and being arranged to engage with the interior surface of the flange under the effect of the shoe-applying force.

According to a still further feature of the invention an internal shoe drum brake is provided having a pair of rigid arcuate shoes of T-shape in radial section, each shoe being arranged to bear at one end against a fixed abutment or an applying device, and carrying at its other end a terminal member which is shaped to lie against the internal surface of the shoe flange, and has its inner end adjustably held to the shoe web, whereby the adjustable holding means acts as a stop for the terminal member so that as the latter is subjected to the shoe-applying force, said member engages firmly with the interior of the flange portion of the shoe.

Preferably adjusting means for bringing about

lengthening of the shoe comprises a wedge member which is carried by the shoe and is arranged to be moved in a direction substantially parallel with the drum axis, said wedge member conveniently engaging slidably between relatively inclined surfaces formed respectively upon the two parts of the shoe. Thus the wedge member may be interposed between the two parts of the brake shoe so that said wedge member receives braking and/or brake-applying force from one member and transfers it directly to the other member. The wedge member is preferably actuated by a screw having a head or equivalent which is located against axial movement relative to the two parts of the shoe, said screw if desired being arranged to engage with a screw thread in the wedge member and having its head or equivalent formed with a part-spherical surface engaging a corresponding surface carried by the brake shoe, so as to allow said screw to take up a position determined by the wedge member. In the preferred construction the wedge member is adapted to extend into an aperture formed in the web portion of the one part of the shoe, and the other or terminal part of said shoe is thickened at its inner end so that it also extends into said aperture, the wedge member being formed with a sloping surface which, in addition to bringing about the adjustment of the shoe parts, also holds the said parts together under the action of the forces in the shoe when the brake is applied. Further, the terminal member has its outer surface arcuately curved so as to fit snugly within the flange portion of the main part of the brake shoe.

The improved adjusting device is particularly suitable for use in two-shoe brakes where each of the shoes is formed at each end with an arcuate recess arranged to abut against and engage pivotally with the fixed housing of the corresponding one of a pair of diametrically opposed double-acting shoe-applying devices having a "floating" action, which devices are simultaneously actuated during the normal application of the brake so that both shoes operate in a leading sense during each direction of rotation of the drum.

A brake of this form will now be described as an example of the invention with reference to the accompanying drawing, in which:

Figure 1 is a side elevation of a brake assembly shown partly in section;

Figure 2 is a fragmentary sectional plan taken on the line 2—2 of Figure 1; and

Figure 3 is a fragmentary side elevation corresponding to Figure 2 when seen in the direction of the arrow A, the back plate being removed.

5 A circular back plate 10 serves to support the non-rotating parts of the brake, namely a pair of actuating devices 11 and 12 and a pair of shoes indicated at 13 and 14, these latter being adapted to be spread apart into engagement with 10 a rotatable cylindrical brake drum shown in section at 15. The two shoes 13 and 14 are of identical construction, so that only the shoe 14 will be described in detail. It comprises a main part which is of T shape in cross section and is formed 15 with an arcuate flange 16 carrying a lining 17 in the customary manner. The central limb of the T section constitutes a web 18, and this is shaped at one end with a concave curved surface 19 adapted to mate pivotally with a corresponding curved surface 20 upon the body of the actuating device 12. The web 18 is thickened by the provision of one or more reinforcing plates 21 and the shoe is located against lateral displacement by a plate 22 forming part of the actuating device 12. The latter can be of any convenient form, and in the present example each of said actuating devices 11 and 12 is provided with a pair of hydraulic pistons indicated at 23, 24, 25 and 26, these having packing cups 21. The 30 spaces between the pairs of pistons are fed in common from a master cylinder unit (not shown) or other suitable source of pressure liquid, so that the pistons 23, 24, 25 and 26 tend to be pushed outwards and thus spread the shoes 13 and 14 35 into contact with the drum 15. The actuating devices are, however, essentially of a "floating" nature, for it will be appreciated that the pistons 23 and 24 or 25 and 26 do not necessarily have to move to equal extents when the brake 40 is applied.

The opposite end of the shoe 14 is provided with a terminal member 28, which is generally of arcuate shape and is formed at its extremity with a concave curved surface 29 adapted to 45 engage pivotally with the corresponding surface 30 of the actuating device 11. The outer curved surface 31 of the terminal member 28 is of such radius that it fits snugly against the interior of the flange 16, while a nut and bolt 32 having a 50 spring washer passes through a slot 33 in the web 18 and frictionally holds the terminal member 28 against the main part of the shoe 14 without unduly restricting the sliding movement 55 of these two parts. The terminal member 28 is formed with a pair of strengthening ribs 34 and 35.

The means used for locating the terminal member 28 in relation to the web 18 will be seen more clearly in Figures 2 and 3, and comprises a wedge 60 member 36 which is screw-threaded at 37 for co-operation with a screw 38. The latter is formed with a flange 39 serving as a head, this having a part-spherical surface 40, while a bridge member 41 bearing against the web 18 has a corresponding concave surface 42 so as to enable 65 the flange or head 39 to seat properly. A friction washer 43 is positioned between the concave surface 42 and the surface 40 of the head or flange 39 so that the axial tension created 70 in the screw 38 by the action of the wedge member 36 locks the adjustment against the effects of vibration. A thin sheet metal plate 44 formed with a resilient detent 45, as will be seen in Figure 3, is secured to the bridge member 41 by 75 welding or riveting. This detent is bent as shown

to engage with a series of notches 46 formed in the flange or head 39 so as to locate the screw 38 and also give an audible indication of the extent to which said screw is rotated during adjustment of the brake shoe. The screw 38 has 5 an extension 47 which is squared at its extremity for the engagement of a spanner, said extension 47 being arranged to pass through a slot 48 in the back plate 10 so as to permit the requisite movements of the brake shoe 14. The wedge 10 member 36 is arranged as shown to extend through an aperture 49 in the web 18 and is formed with a surface 50 extending parallel with the axis of the screw 38, said surface being adapted to slide upon the interior of the said 15 aperture 49 as the screw 38 is rotated. An oblique surface 51 upon the wedge member 36 engages with a corresponding surface 52 upon the end of the terminal member 28, so that tightening of the screw 38 pulls the wedge member 36 through 20 the aperture 49 and causes the terminal member 28 to slide upon the web 18, thus increasing the effective length of the shoe 14. The end of the terminal member 28 is thickened as indicated at 53 so as to extend into the aperture 49. 25 The shoe 13 is also provided with a terminal member 28, which is held against the web 18 of said shoe by a locating nut and bolt 32 and a corresponding wedge member 36, the construction and operation of which are similar to those 30 of the shoe 14. The back plate 10 is fitted with a pair of studs 54 and 55 serving as anchorages for pull-off springs 56, 57 for the shoe 13 and 58, 59 for the shoe 14.

When pressure liquid is fed to the actuating 35 devices 11 and 12 while the drum 15 is rotating in, say, a clockwise direction, the shoes 13 and 14 are brought into contact with the drum and are carried round therewith until the curved surface 19 of the shoe 14 and the corresponding 40 surface of the shoe 13, indicated at 60, engage with the fixed parts of the actuating devices 13 and 11 respectively. The opposite ends of the two shoes are in the meantime forced outwards against the drum by the pistons 24 and 25 so 45 that both of the shoes 13 and 14 act in a leading sense. In a similar manner, during clockwise rotation of the drum 15 both shoes again act in a leading sense, the shoe 13 anchoring against the actuating device 12 and the shoe 14 50 anchoring with the fixed part of the actuating device 11.

In all circumstances when the brake is applied the forces acting on each shoe tend to shorten the effective length of the shoe by causing the terminal member 28 to slide upon the web 18. This tendency is, however, efficiently resisted by the wedge member 36, which latter is gripped between the end of the terminal member and the edge of the aperture 49 so that force 60 is efficiently transmitted from one part of the shoe to the other without straining the adjusting screw 38. The inclination of the wedge surface 51 is arranged in such a sense that the terminal member 28 is at all times pressed firmly 65 against the web 18, and of course the applying force and the braking force received by the shoe both tend to force the terminal member 28 firmly against the interior of the flange 16, thus rendering the construction particularly rigid 70 during operation. Despite this effect, the wedge member 36 is only moderately gripped owing to the action of the pull-off springs when the brake is "off," and therefore only a slight force is necessary to turn the screw 38 in order to ad- 75

just the clearance between the linings of the brake shoes 13, 14 and the drum 15.

I claim:

1. An internal shoe drum brake comprising a pair of rigid arcuate shoes of T-shape in radial section, a non-rotatable back plate, a pair of diametrically opposed double-acting shoe-applying devices having a "floating" action, which devices comprise fixed housings and are simultaneously actuated during the normal application of the brake so that both shoes operate in a leading sense during each direction of rotation of the drum, a concave surface at one end of each shoe engaging pivotally with a convex surface upon the fixed housing of the adjacent applying device, a terminal member for each shoe arranged to lie against the shoe web and to engage with the interior of the flange of the shoe, said terminal member being shaped at its outer end with a concave surface engaging pivotally with the fixed housing of the other applying device, and adjusting means acting as a stop between the shoe and the terminal member, but arranged to shift the terminal member relative to the shoe for modifying the lining clearance.
2. An internal shoe drum brake comprising a rotatable drum, a non-rotatable back plate, a pair of rigid arcuate shoes each pivotally connected at one end with the back plate, said shoes being of T-shape in radial section with the web directed radially inwards, a frictional lining secured to the flange of each shoe, applying means mounted upon the back plate to urge the shoes into engagement with the drum, a terminal member operatively interposed between each shoe and the corresponding applying means, and wedge adjustment means mounted upon the

shoe and arranged to cooperate with the end of the terminal member to shift said member along the shoe and thus vary the lining clearance by modifying the effective length of the shoe measured from the pivot to the applying means, the terminal member being arranged with an outer curved edge which lies snugly in engagement with the interior surface of the brake shoe flange and is urged thereagainst by the force of the applying means.

3. An internal shoe drum brake according to claim 2, wherein the wedge adjustment means comprises a tapered block extending through an aperture in the shoe web, screw means for drawing the block through the aperture, on surface of said block engaging slidably with the edge of said aperture and lying substantially at right angles to the shoe web, while the opposite surface is arranged obliquely and engages the end part of the terminal member, the said end part of the terminal member being thickened to provide an oblique surface which lies within the aperture and is disposed in the general plane of the shoe web.

4. An internal shoe drum brake according to claim 2, wherein the wedge adjustment means comprises a wedge member, a screw threaded into said wedge member and having a head, and a member which is carried by the brake shoe and is arranged to engage with the under surface of the screw head, wherein said under surface of the screw head is of part-spherical shape and is arranged to mate with a corresponding part-spherical concave surface formed in the member carried by the brake shoe.
